Des. 241,378
Patented Sept. 7, 1976

241,378

X-RAY GONADAL SHIELD PLATE

William Burger, 48 Roland Road,
Jamestown, N.Y. 14701

Filed Mar. 10, 1975, Ser. No. 556,657

Term of patent 14 years

Int. Cl. D24—99

U.S. Cl. D83—1 H

Fig. 2.

Fig. 4.

Fig. 1.

Fig. 5.

Fig. 3.

FIG. 1 is a top plan view of an X-ray gonadal shield plate showing my new design; and

FIGS. 2-5 are edge elevational views thereof.

The non-illustrated bottom plan view is identical to the illustrated top plan view thereof.

I claim:

The ornamental design for an X-ray gonadal shield plate, as shown and described.
